The ornamental design for a teething ring, as shown and described.

DESCRIPTION

FIG. 1 is a front view of the teething ring showing the design of my invention;

FIG. 2 is a top view thereof; and,

FIG. 3 is a right side view thereof.

The rear view is a mirror image of the front view;

The bottom view is a mirror image of the top view; and,

The left side view is a mirror image of the right side view.
